UNITED STATES PATENT OFFICE.

GEORGE H. PALLADY, OF ALLERTON, IOWA.

BROOM AND BRUSH CUTTER.

No. 826,056.

Specification of Letters Patent.

Patented July 17, 1906.

Application filed June 8, 1905. Serial No. 264,288.

To all whom it may concern:

Be it known that I, GEORGE H. PALLADY, a citizen of the United States, residing at Allerton, in the county of Wayne and State of 5 Iowa, have invented certain new and useful Improvements in Broom and Brush Cutters; and I do declare the following to be a full, clear, and exact description of the invention, such as will enable others skilled in the art to which 10 it appertains to make and use the same.

My invention relates to improvements in cutters for brooms and brushes; and it consists in certain novel features of construction, combination, and arrangement of parts hereinafter described and claimed.

The object of the invention is to provide a simple, inexpensive, and durable device of this character by means of which brooms or brushes of various sizes may be quickly and 20 effectively trimmed or cut off with rounded ends.

The above and other objects, which will appear as the nature of my invention is better understood, are accomplished by means of the 25 construction illustrated in the accompanying drawings, in which—

Figure 1 is a perspective view of a broom or brush cutter constructed in accordance with my invention. Fig. 2 is a top plan view, 30 on an enlarged scale, of the adjustable curved cutter-blade and its coacting adjustable cutter-block. Fig. 3 is a vertical transverse sectional view through the same. Fig. 4 is a longitudinal sectional view through the cutter-blade or knife; and Fig. 5 is a perspective view of the two sections of the cutter-block, showing said sections detached from each other.

Referring to the drawings by numeral, 1 40 denotes my improved trimmer or cutter for brooms, brushes, and the like, which comprises a suitable frame or support 2, a curved adjustable cutter-block 3, mounted upon one end thereof, and a similarly-curved adjustable cutter or knife 4 to coact with said block. The frame or support 2 comprises a base-board or table 5, supported horizontally 45 upon legs and having upon its top upright side pieces 7 adjacent to the end at which the 50 cutter-block is mounted and at its opposite

end a transverse support 8, formed with a central notch or groove 8^a, adapted to receive the handle of a broom.

The cutter-block 3 and the knife 4 are curved for the purpose of cutting rounded 55 ends or bottoms upon the brooms, and they are made adjustable to adapt them to cut or trim brooms of different widths or sizes. The cutter-block 3 is preferably constructed of two slidably-engaged sections 9 and 10. 60 The section 9 is formed with a longitudinally-extending groove 11, which is adapted to receive a longitudinally-curved tongue 12, formed upon the section 10. These sections are adapted to be held in an adjusted position 65 by means of a clamping-bolt 13, which is passed through alining openings 14, formed in the section 9, and through a longitudinally-extending slot 15, formed in the tongue 12. This construction is clearly shown in the 70 drawings; but it will be understood that any other suitable means may be provided for adjusting the two sections of the cutter-block to receive brooms of different widths.

The curved adjustable knife or cutter 75 blade 4 is composed of two slidably-connected sections 17 18, which are adjustable upon each other, as shown at 19, and which are secured upon a transversely-swinging lever 20, pivoted at 21, upon one side of the 80 table 2 and formed with a handle 22. This adjustment of the knife permits the same to adapt itself to the adjustment of the cutter-block, as will be readily understood.

From the foregoing description, taken in 85 connection with the accompanying drawings, the construction and operation of the invention will be readily understood without requiring a more extended explanation.

Various changes in the form, proportion, 90 and the minor details of construction may be resorted to without departing from the principle or sacrificing any of the advantages of this invention.

Having thus described my invention, what 95 I claim as new, and desire to secure by Letters Patent, is—

1. A brush or broom cutter having a laterally-curved cutter-block and a coacting laterally-curved knife.

2. A brush or broom cutter having a longitudinally-extensible cutter-block.
3. A brush or broom cutter having an adjustable cutter-block, consisting of two sliding sections, means for adjusting said sections to receive brooms of different widths, and a knife coacting with the cutter-block.
4. A brush or broom cutter having a cutter-block consisting of two longitudinally-curved and slidably-engaged sections, means for ad-

justably securing said sections together, and a knife coacting with the cutter-block.

In testimony whereof I have hereunto set my hand in presence of two subscribing witnesses.

GEORGE H. PALLADY.
